ARROW FOR ARCHERY

Filed July 5, 1927

UNITED STATES PATENT OFFICE

ROBERT H. COWDERY, OF GENEVA, OHIO, ASSIGNOR TO THE AMERICAN FORK & HOE COMPANY, OF CLEVELAND, OHIO, A CORPORATION OF OHIO

ARROW FOR ARCHERY

Application filed July 5, 1927. Serial No. 203,425.

My invention relates to arrows for archery, and relates particularly to the provision of an arrow adaptable to be used for target and hunting purposes, and which may be produced in quantities with uniformity in the qualities of weight, balance, and in straightness as well as having uniform air friction effects.

Heretofore, arrows have been made of many different materials, and effort has been made to accomplish the production of an arrow, metallic in whole or in part, and in which one or more of the above qualities was sought to be obtained.

These efforts have, so far as I know, left much to be desired in the effort for achievement of all of the above qualities in an arrow responding to the requirement of present day practice.

For instance, at the present time, an arrow adaptable for competitive target, clout and distance shooting, is usually about 28 inches long and may weight the equivalent of 4 shilling and 9-pence in new English silver, and the "bob-tail" comprises three feathers each curving the same way and usually about $1\frac{1}{2}$ inches long and $\frac{1}{2}$ inch deep, and preferably are made of seasoned red deal and although may be "self" very often are "footed"; that is, a piece of hard wood to which the pile or point is attached is spliced to the deal shaft, which of course must be perfectly straight and stiff. This construction involves the making of the shaft to a uniform diameter of approximately $\frac{3}{2}$ of an inch.

The archery associations have set up certain specifications, not differing greatly from the above, for arrows used for competitive archery, but it is found very difficult to make arrows of wood or other materials suitable for the purpose, adaptable to conform to such specifications, and in using deal or other seasoned wood, difficulty is had in achieving the desired straightness, weight and balance, and even more difficulty is had in maintaining the desired straightness in an arrow after making, during and pending use. Wood is very susceptible to warping and many expedients have been adopted, such as storing the ar-

rows in closed cases and whereby all sides of the arrow are exposed to the same temperature and humidity conditions. Archers, however, are prone to disregard the safeguards which minimize but which may not prevent warping, with the result that the arrows must be very carefully selected before each competition, many being thrown out as unfit, which have cost much in production and maintenance up to the time of competition.

An object of my invention is to accomplish the production of an arrow of a form capable of being made in quantities, with substantially uniform results as to weight, balance, and a high degree of straightness and to provide for the mounting thereon of the necessary pile, bob-tail and nock.

Another object of my invention is to provide an arrow having the aforesaid qualities and which will maintain such qualities through indeterminate periods of use or non-use and without requiring the care now required to maintain arrows free from warping.

Another object of my invention is to provide an arrow hardy enough to withstand the forces incidental to its use without substantial variation in form.

Other objects of my invention and the invention itself will be apparent by reference to the following description of certain embodiments of my invention and which are illustrated in the accompanying drawings.

Referring to the drawings:

Fig. 1 is an elevational view of an embodiment of my invention;

Fig. 2 is a fragmentary elevational view of the embodiment of Fig. 1, the view illustrating substantially the actual size of the same;

Fig. 3 is a transverse sectional view taken on the line 3-3 of Fig. 2;

Fig. 4 is an enlarged fragmentary sectional view of a modified construction of a nock;

Fig. 5 is a transverse sectional view taken on the line 5-5 of Fig. 4;

Fig. 6 is a longitudinal sectional view of a modified feather mounting;

Fig. 7 is an end elevational view of the embodiment of Fig. 6;

Fig. 8 is a fragmentary view partly in sec-

tion of another modification of the feather mounting;

Fig. 9 is a transverse sectional view taken on the line 9—9 of Fig. 8;

5 Fig. 10 is a fragmentary view partly in section of another form of the feather construction;

10 Fig. 11 is a fragmentary view partly in section of still another modification of the feather construction;

Fig. 12 is a transverse sectional view taken on the line 12—12 of Fig. 11;

15 Fig. 13 is a transverse sectional view taken on the line 13—13 of Fig. 11;

20 Fig. 14 is a fragmentary view mostly in longitudinal section of a modified construction of the pile; and

25 Fig. 15 shows a modified form of shaft having an exterior sound vibration subduing 20 coating.

Referring to Figs. 1, 2 and 3, wherein like parts are designated by like reference characters, in which figures I illustrate one embodiment of my invention, preferably comprising a shaft 10, formed of a light tubular metallic material, such as a seamless tube of steel having a relatively thin wall and a diameter sufficiently small to render the same of light weight, while at the same time of sufficient thickness to insure durability thereof. The diameter of the shaft is preferably of equal dimensions at each end of the same. At 30 11, I show an impact pile preferably in the form of a bullet head and formed of hollow steel, or the like, having a pointed end and having the opposite end thereof reduced in its transverse dimensions at 12, the reduced portion being telescoped into the end of the shaft with the shoulder 13 thereof engaging 35 the end of the tube. Suitable means may be employed for securing the pile onto the tube, such as by welding the same thereon, or by soldering the joint, at 14, a quantity of lead or the like may be placed within the head adjacent the point to properly balance the arrow, somewhat similar to the manner illustrated 40 in Fig. 14.

45 A nock 15 having a portion slotted at 16, and a reduced portion 17, is provided, said reduced portion being telescopicable into the bore of the tubular shaft as shown at 18, with the shoulder 19 thereof engaging the end of the shaft opposite to the pile receiving end. The slot 16 may receive a bow string therein 50 for propelling the arrow in use. The nock may be formed of a fibrous material, such as compressed paper or the like, and thus a possibility of the same cutting the bow string will be nil. The nock may be so secured in 55 the shaft by striking the end of the shaft a slight blow to form a small turned-in portion in the shaft.

60 A feathering for guiding the arrow during its flight through the air is provided and disposed on the tubular shaft adjacent to the

70 nock end thereof, the feathering being secured thereon, preferably by a wrapping 20 of thread, or the like, wound spirally about the shaft and covering a portion of the surface thereof, a distance of substantially 2½ inches in length. This wrapping provides a supporting base for a plurality of feathers 75 preferably three in number, equally spaced from each other, the quill 22 thereof being secured to the wrapped base by a suitable cement, glue or the like adhesive material, and with the projecting ends of the quills further secured to the base by a thread spirally wound about the same and the shaft, at 24 and 25. The quills extend longitudinally 80 along the shaft surface with the feather vanes 21 projecting radially thereof. Each of these vanes is naturally bent in a very slight curve in the same direction from their forward end toward their rear end and forms a screw propeller which may effect rotation of the arrow during its flight through the air and thus increase its precision and projectibility. However, these vanes may be secured so that the natural curvature of the same is straightened. If desired, the edges of the vanes may be trimmed, as shown, however, they may be left with straight edges.

85 I have found that a tubular shaft having a length of 25⅞ inches, possessing a diameter of $\frac{3}{2}$ of an inch throughout its entire length and having a wall thickness throughout its length of substantially .0075 of an inch is well adapted for use in the formation of an arrow, and I have found that an arrow having these 90 dimensions gives highly satisfactory results. This length added to the length of pile and nock may give a desired total length of 28 inches. However, it is to be understood that I may depart from the dimensions herein 95 given and I do not wish to be limited to these dimensions as they are given merely for the purpose of illustration and to enable a more thorough understanding of my invention. 100 My improved arrow is well adapted to conform to specifications in vogue promulgated by the various archery associations.

105 The reduced portion of the nock provides a stopper for the tubular shaft to prevent the ingress of moisture, water or the like, from entering the tubular shaft and thus eliminates 110 possibility of the tubular shaft being deteriorated from the inside outwardly by rusting, or the like. The outer surface of the tubular shaft may be covered with a protective coating to prevent the deteriorating efforts of the elements from attacking the tubular shaft from its exterior surface. A high metallic polish may also be applied to the tubular shaft and thus decrease air friction of the arrow during its flight through the air and thereby increasing its range and precision.

115 Referring to Figs. 4 and 5 of the drawings, I have shown a modified form of nock which 120 might be employed in place of the nock illus-

trated in the embodiment of Fig. 1. This nock is preferably formed in the end of the shaft 10' by cutting a slot 30 therein and in bending the edges of the bifurcated portions 5 of the shaft, thus formed, inwardly at 31 and 32, and rounding the same at their extremities 33. The slot and side wall portions may be machined and all sharp corners and burrs may be removed during such a machining operation thereon, and accordingly the nock will not cut or fray the bow string in use.

A plug 34 of wood or other fibrous material may be inserted into the shaft bore 35, beyond the nock and thus form a stopper to 15 prevent the ingress of moisture or water into the shaft and thereby eliminating the possibility of the tubular shaft rusting or deteriorating from the interior outwardly.

Referring to the embodiment of Figs. 6 and 20 7, I show a second scheme for fletching an arrow, preferably comprising a nock 40 of wood or the like, such wood as deal, spruce and basswood, which has been found to give 25 very high efficient results in use. One end of the nock 40 is reduced in its transverse dimensions at 41, to form a plug which is telescoped within the bore of the shaft 10", with the shoulder 42 of the nock engaging the end of the shaft. The telescoped portion of the plug 30 is of a size sufficient to be self-retaining in the bore of the shaft when placed therein, however, the shaft may be punched slightly inwardly at 48 to insure against displacement thereof, and thus a closure for the end of 35 the shaft bore to prevent the ingress of moisture therein is provided. The opposite end of the nock 40 is slotted at 43 for the bow string. The outer surface of the nock is preferably highly polished prior to placing the 40 feathers thereon. The feathers are preferably three in number, of equal size, and equally spaced from each other, with their quills 44 engaging the nock and extending longitudinally along the exterior surface of 45 the same, and secured thereto by a suitable cement, glue or the like adhesive material, with the projecting ends of the quills further secured to the plug by a wrapping of thread, 50 shown at 45 and 46. The vanes 47 of the feathers extend radially of the nock and are naturally slightly curved and form a screw propeller. These vanes may be trimmed if desired, as illustrated in the drawings.

Referring now to Figs. 8 and 9, wherein I 55 show still another manner of fletching the arrow, which I accomplish by forming longitudinally extending grooves 50 in the tubular shaft adjacent the nock 51 thereof, these 60 grooves being formed by drawing the end of the tube through a plurality of rollers. Into these grooves I insert the quill 52 of the feathers and secure the same therein by a cement, glue or other suitable adhesive, and 65 I then further secure the projecting ends of the quills by wrapping a thread about the

same, as shown at 53 and 54. The vanes 55 of the feathers extend radially of the shaft and may also be slightly curved to provide a screw propeller for the arrow.

Referring now to Fig. 10 of the drawings, 70 I show a fourth manner of fletching the arrow which comprises stippling or knurling the exterior surface of the shaft at 60 prior to the insertion of the nock 61 into the end thereof. This stippled or knurled portion of the 75 shaft permits the quills 62 of the feathers to be secured directly to the metal, by virtue of a cement, glue or other suitable adhesive material, it having been heretofore found that the quill cannot be readily cemented directly 80 to the smooth surface of the metallic tubular shaft. I may further secure the projecting ends 63 of the quills by wrapping a thread about the same as in the foregoing embodiment, however, I may dispense with this and 85 secure substantially the same results.

Referring next to the embodiments of Figs. 11, 12 and 13, wherein I illustrate still another scheme for fletching the arrow, which comprises forming three slots 70 in the end 90 of the tubular shaft extending longitudinally therein a distance substantially three inches and in then telescoping a wooden nock 71 into the end of the tubular shaft having its periphery formed of spaced flattened portions 95 and each disposed directly opposite to the slots 70 of the tubular shaft when so telescoped. Prior to the insertion of the nock 71, I secure the quills 73 of the feathers on the flattened portion 72 of a suitable cement or 100 other adhesive material and I then insert the nock 71 into the tubular shaft with the vanes 74 of the feathers aligned in the slots 70 and extending radially therethrough. The flattened portions of the plug are sufficiently depressed to permit the ends 75 of the quills to extend into the tubular shaft beyond the slots 70 thereof and thus I provide additional securing means for the feathers. The plug 105 portion 80 of the nock is cylindrical and of 110 a diameter sufficient to seal the end of the shaft bore.

As best shown in Fig. 13 of the drawings, the nock 71 may be secured in the tubular shaft against accidental disengagement 115 therefrom, and the slotted end portion 78 of the tubular shaft may be secured against spreading radially by the application of a solder or the like at localized points such as at 76 in the slots adjacent the nock 79. The 120 nock end may be slotted at 77 for the reception of the bow string.

Referring now to Fig. 14 of the drawings, I show a modification of the pile construction of an arrow of the foregoing embodiment, 125 which comprises inwardly swaging the end of the tubular shaft 90 at 83 to closely approximate a point at 81, and in then filling the small aperture remaining in the end of the tube with solder 83, or the like, to insure 130

proper balance of the arrow and also to seal the end thereof against the ingress of moisture into the shaft.

In Fig. 8, I show, disposed within the tubular walls of the shaft, a filling extending throughout the entire length of the shaft from the stem 12 of the pile to the stem 17 of the nock element. This filling, 85, is of a sound deadening material such as cork, asbestos wool, or the like, and it is understood that I may and do contemplate sometimes supplying this filling to shafts showing other methods of securing the feathering than that shown in Fig. 7 and may be employed in connection with any tubular arrow, the object of such filling being to deaden vibrations of the metallic material of the shaft walls, to the end that any vibrations otherwise accomplishing a ringing metallic sound may be so subdued that such sound will not be objectionably present. When the feathering is secured in the manner illustrated in Fig. 11, I sometimes contemplate employing this filling throughout the interior of the shaft, replacing, incidentally, the element 80, the filling 85 performing its function of holding the feathering.

In Fig. 15, I show a fragment of a shaft 10 wherein I apply a coating of cellulose 100 to the exterior of a metallic tube, which I find is also effective to subdue such vibrations. I contemplate sometimes employing the filling and coating in a single arrow, and it will be understood that in all cases I maintain the same exterior diameter by reducing the diameter of the metallic tube by the amount of the wall thickness of the cellulose coating when applied, and that I may reduce the thickness of wall of the tube to compensate for any difference in weight resulting from the addition of the filling, coating, or both.

Improved arrow constructions employing the nock substantially as shown in Figs. 3, 4 and 5 and the pile construction shown in Fig. 14 are not specifically claimed herein, being claimed specifically in my co-pending application, Serial No. 472,449, filed August 1st, 1930, which is a division hereof.

Having thus described my invention in certain specific embodiments, I am aware that numerous and extensive departures may be made from the embodiments herein illustrated and described without departing from the spirit of my invention.

I claim:

1. An arrow comprising a pile and shaft, the shaft being in the form of a metallic tube, a nock affixed to an end of the tube remote from the pile and a feathering comprising a plurality of feathers each having an attached supporting quill base affixed at intervals around the nock end of the shaft, said shaft being slotted at spaced intervals to receive the quill base of each feather with the feath-

ering projected through the slits, and a filling of inherently compressible material for the portion of the shaft underlying the feathering to maintain internal pressure against the internal surfaces of the quill bases thereof.

70

2. An arrow for archery comprising a metallic shaft, and a filling for the shaft of relatively non-sound conducting material.

75

3. An arrow for archery comprising a metallic shaft, a filling and a coating for the interior and exterior of the shaft, each of relatively non-sound conducting material.

80

4. An arrow for archery comprising a metallic shaft, a filling and a coating for the interior and exterior of the shaft, one being of relatively non-sound conducting material.

85

5. An arrow for archery comprising a tubular metallic shaft and vibration deadening material extending longitudinally of the shaft in engagement with its wall to subdue metallic vibrations thereof.

85

6. An arrow having a tubular metal shaft formed with axial slits at its feathered end, and feathers insertable endwise into said slits, the veins of the feathers being within the shaft and wider than the slits for the purpose specified, and a plug of relatively sound vibration dampening material disposed within the shaft against the said veins to retain them in position.

95

7. An arrow having a tubular metal shaft formed with axial slits at its feathered end, and feathers insertable endwise into said slits, the veins of the feathers being within the shaft and wider than the slits for the purpose specified, and a plug of relatively sound vibration dampening material disposed within the shaft against the said veins to retain them in position, said plug projecting anteriorly from the end of the shaft and having its exteriorly projecting end slotted to form a nock for the arrow.

100

In testimony whereof I hereunto affix my signature this 22 day of June, 1927.

ROBERT H. COWDERY.
